UNITED STATES PATENT OFFICE.

FRED F. MESS, OF FARMINGTON, MINNESOTA.

HAYRACK LADDER.

Application filed October 17, 1925. Serial No. 62,994.

My invention relates to a hay rack ladder which is primarily adapted to be attached to the end of the rack to form a ladder for the rack which is rigidly supported so that the farmer may have no fear of the rack being jarred or dropped out of place while he is driving along with the rack empty. It is quite undesirable to have a hay rack end ladder which will drop down while driving the horses and thus being apt to cause an accident.

It is also a feature of my invention to provide a hay rack ladder which is made adjustable so that it can be adjusted to different widths of racks without changing the general construction of the same. In carrying out this feature of my invention, I provide cross members having a series of holes which are adapted to be attached to the upright frame member so as to rigidly support the cross members which form the steps of the ladder, and the members forming the end of the rack to assist in holding the hay in place.

My invention also includes a metal frame member which is of a peculiar shape, having a loop at the top which permits the frame to be easily bent and adjusted to provide a wider or narrower width so as to fit between the stringers of the rack when the frame is attached thereto. The stringers are centrally disposed and spaced apart in the rack and are adapted to carry on the end the ladder frame which is rigidly bolted to the same. Different sized racks require different widths of frame and cross members and in my invention I have provided means for accomplishing this result.

These features together with other objects and detail of construction will be more fully and clearly set forth in the specification and claims.

In the drawings forming part of this specification;

Figure 1 is a perspective view of a portion of a hay rack showing my ladder and adjustable end attached thereto.

Figure 2 is a front view of my ladder.

Figure 3 illustrates one of the cross members.

Figure 4 illustrates the frame with a different shape as it would appear when the cross members are disengaged from the same.

In the drawings my hay rack ladder A is made up of a metal frame B which is pro-

vided with a top compensating loop 10 and from which depend and extend side members 11.

The side members 11 are spaced apart and are provided with inwardly extending ends 12 which are adapted to engage against the stringers 13 of the hay rack C. Only a portion of the hay rack is illustrated in the drawings.

The compensating loop 10 provides means whereby the sides 11 can be spaced farther apart if it is desired or drawn together to make a narrower frame B so as to permit the ends 12 to properly fit between the stringers 13. In attaching my ladder end A to the hay rack C it is desirable that the ends 12 be bolted securely to the stringers 13. The framework B is made of metal which is sufficiently strong to support the end ladder A rigidly in an upright position projecting from the ends of the stringers 13, and in a manner so that even when the hay rack is empty the farmer can stand on the hay rack and be supported against danger of falling by engaging the frame B.

The loop 10 permits the farmer to divide the lines of the horses so that he can place them on either side and if he wishes can attach them to the loop, and the shoulders formed by the horizontally extending portions 14 which connect the loop 10 with the side members 11, provide a horizontally disposed shoulder on either side of the loop 10.

The ends 12 bend outwardly, as illustrated in Figure 2, so that in attaching the same to the stringers 13 the frame B is held under spring tension by the compression of the ends together between the stringers 13. This provides more rigidity to the frame and permits adjustment for compensating for different widths between the stringers to a limited degree. When a greater width for the frame B is required between the members 11, the loop 10 can be suspended by bending the same apart and thus provide for the desired width for the frame B.

I provide cross arms 15, any number of which can be used, and which are attached to the frame B through the openings 16. In each cross arm 15 I provide a series of openings 16 extending near the end thereof so that the cross members can be adjusted readily to the width of the frame between the members 11. The adjustable means of my hay rack ladder end is quite important as it permits me to make and carry a stock

of these ends in a knocked-down condition which can be shipped to the farmer and which the farmer can attach to a hay rack as he desires. This is a preferable construction as the farmer usually desires to make up his own hay rack. Further, it is a desirable feature because it permits me to supply the farmer who already has a hay rack but who desires to use my ladder end on his hay racks.

In Figure 4 I illustrate my frame B made with a round-spring like loop so that it can be readily adjusted to the desired width for compensating for various sizes of hay racks as to the distance between the stringers I3.

The simplicity of my adjustable ladder and hay rack end is quite apparent, yet the effectiveness in operation is such that I provide a hay rack end which is very desirable, inexpensive to manufacture and easily attached to practically any hay rack.

In accordance with the patent statutes I have described the principles of operation in carrying out my invention and while I have illustrated a particular formation of my adjustable hay rack ladder end, I desire to have it understood that the drawings are only illustrative and that the invention can be applied to uses other than those above set forth within the scope of the following claims.

I claim:

1. A hay rack end including, a metal frame member formed of spring material, a compensating loop, side members adapted to be spaced apart by said compensating loop, attaching ends bent to extend from said side members to permit said frame to be attached to the stringers of a hay rack, and

cross arms having a series of openings 46 formed therein to permit the adjustment of the cross arms in relation to the width of the side members of said frame.

2. A hay rack ladder including, a metal frame having side members extending approximately parallel, horizontally disposed portions adapted to form shoulders at the top end of said side members, a loop between said horizontally disposed members adapted to compensate for adjusting the width of 50 the side members and adjustably securable cross arms adapted to form the cross arms for said ladder.

3. A hay rack ladder including, a loop frame formed from a single piece of metal, 55 and having side members spaced apart, securing ends formed on said frame extending approximately at right angles to said side members and a compensating loop positioned between said side members in a manner to permit the width of the frame to be adjusted.

4. A hay rack ladder comprising a frame made from a single piece of material, ends bent outwardly at the base of the side members of said frame, said frame being approximately three sides of a rectangle with side members extending approximately parallel when attached and adapted to spring outwardly away from each other at the 70 free ends of the frame when free from the hay rack, a loop formed in the side of said frame adapted to compensate for adjustment of the ends and a series of cross arms adapted to form adjustable ladder bars 75 adapted to be secured to said frame.

FRED F. MESS.
